UNITED STATES PATENT OFFICE.

HUBERT G. HUSTED, OF OBERLIN, OHIO.

DESIGN FOR AN INDIVIDUAL COMMUNION-CUP.

SPECIFICATION forming part of Design No. 27,455, dated August 3, 1897.

Application filed June 30, 1897. Serial No. 643,038. Term of patent 7 years.

To all whom it may concern:

Be it known that I, HUBERT G. HUSTED, a citizen of the United States, and a resident of Oberlin, county of Lorain, State of Ohio, have invented certain new and useful Designs for Individual Communion-Cups, of which I hereby declare the following to be a full, clear, and exact description, such as will enable others skilled in the art to which it appertains to make and use the same, the following being a specification, reference being had to the accompanying drawings.

Figure 1 is a side elevation of a cup showing my design. Fig. 2 is a top view thereof, 15 and Fig. 3 is a rear elevation.

As shown in the drawings, the leading or material feature of my invention consists of a widely-projecting lip connected with the body of the cup by a sloping line in the front of the cup and a deep notch in the back of 20 the rim of the cup, all the rim of the cup being horizontal except in the rear. The body of the cup has a somewhat floral shape, tapering gradually toward the base, and annually withdrawn near the bottom to form a 25 more slender neck. The base is cylindrical and an outwardly-curved surface connects it with the neck.

In the figures, 1 is the body of the cup; 2, the cylindrical base; 3, the outwardly-flaring lip; 4, the narrowed neck; 5, the notch in the rear of the rim, and 6 the curved surface, which connects the base with the narrowed neck.

The design is shown as plain, but could be 35 engraved or ornamented to give a greater floral effect by curved lines on the surface representing the edges of petals or calyx, or the veins in the petals, or could be otherwise 40 ornamented.

This design may also be applicable to other cups than communion-cups, or other articles, such as pitchers, &c.

Having described my invention, what I claim as new, and desire to secure by Letters 45 Patent, is—

The design for an individual cup for communion-service, as herein shown and described.

HUBERT G. HUSTED.
